Primary Examiner — John R Yeh(74) *Attorney, Agent, or Firm* — Mark C. Johnson; Johnson Dalal(57) **CLAIM**

The ornamental design for a laundry ball, as shown and described.

DESCRIPTION

FIG. 1 is a left, front perspective view for a laundry ball in accordance with the present invention;

FIG. 2 is a bottom, front perspective view thereof;

FIG. 3 is a top plan view thereof;

FIG. 4 is a bottom plan view thereof;

FIG. 5 is a left side elevation view thereof, the right side view being identical thereof; and,

FIG. 6 is a front elevation view thereof, the rear view being identical thereof.

The broken lines in the drawings depict portions of the laundry ball that form no part of the claimed design.
